SURGICAL RETRCTOR UNIT

Georg Förster, 4 Stresemannstrasse,
68 Mannheim, Germany

Filed Mar. 25, 1968, Ser. No. 11,114

Claims priority, application Germany Dec. 27, 1967

Term of patent 14 years

Int. Cl. D24—03

U.S. Cl. D83—12

FIG. 1

FIG. 3

FIG. 2

FIG. 1 is a top perspective view of the surgical retractor unit; and

FIG. 2 is a bottom perspective view of the surgical retractor unit;

FIG. 3 is a cross-sectional view, taken on line III—III of FIG. 1, to a reduced scale, of the surgical retractor unit, with the facing clamp omitted for clarity of illustration.

I claim:

The ornamental design for a surgical retractor unit, as shown and described.
